UNITED STATES PATENT OFFICE.

CARL LAWRENCE MATTISON, OF ROCKFORD, ILLINOIS, ASSIGNOR TO MATTISON MACHINE WORK, OF ROCKFORD, ILLINOIS, A CORPORATION OF ILLINOIS.

WOOD-TURNING MACHINE.

Application filed May 11, 1925. Serial No. 29,314.

The method in common use for supporting the stick to be turned consists in mounting the stick between a spur center and a cup center, the stick being caused to revolve by means of power applied to the spur center. When so supported rotation of the stick at high speed produces torsional stresses which set up vibration or chattering, thus producing "chatter marks" which cannot be removed even by sanding. Moreover, the twisting stresses resulting from the fact that the stick is driven from one end only may become so great that a slender piece of work may break.

15 The object of my invention is to provide, in a wood turning machine, means whereby both ends of the stick are positively driven in synchronism, to the end that a high rate of production may be attained without sacrificing quality.

In the accompanying drawings, I have illustrated a preferred embodiment of my invention, but it should be understood that it is not intended to limit the invention to 25 the particular construction and arrangement shown, it being contemplated that various changes may be made by those skilled in the art without departing from the spirit and scope of the invention as expressed in 30 the appended claim.

Figure 1 is a fragmentary front elevational view partially in section, of a wood turning machine embodying my invention.

Fig. 2 is a fragmentary elevational view 35 of one end of the machine, the driving shaft being shown in section.

Fig. 3 is a fragmentary elevational view looking from the opposite end of the machine.

40 Fig. 4 is a fragmentary sectional view illustrating a detail of construction on an enlarged scale, the view being taken approximately in the plane of line 4-4 of Fig. 1.

45 The machine herein shown for purposes of illustration comprises a main frame or base 7 on which is mounted for rotation a cutter spindle 8 upon which is supported a cutter 9 shown diagrammatically in Fig. 1.

50 The work is supported upon a swinging table 10 mounted for movement toward and away from the cutter. The table 10 is carried upon the upper end of an upright frame 11 having its lower end pivotally

supported in suitable bearings 12 at the 55 lower forward side of the base.

Means is provided for swinging the table toward and away from the frame 7 which in the present instance consists of a rock shaft 50 supported a substantial distance forwardly of the frame 7 upon forwardly extending brackets 51 secured to the frame so as to be adjustable forwardly and rearwardly relative thereto. A pair of lever arms 52 fast on the rock shaft 50 are pivotally connected by links 53 with the frame 11, and one end of the rock shaft has an operating handle or lever 54 whereby the shaft may be rocked and the table thereby moved toward and away from the cutter.

Upon the table are supported a headstock 13 and a tailstock 14, adapted for adjustment in a well known way. The headstock comprises a spindle 15 at the forward end of which is suitably secured a spur center 16 and near the rear end of which is secured a worm wheel 17 enclosed within a suitable housing 18 which also encloses a worm 19 on the upper end of an upright shaft 20. The worm wheel and worm are arranged to mesh for the purpose of transmitting motion from the shaft 20 to the spindle 15, the shaft 20 being operatively connected at its lower end with a drive shaft 21 (Fig. 2) through the medium of bevel gearing 22. A pair of universal couplings 23 and 24 are provided in the shaft 20.

The tailstock 14 comprises a spindle 25 carrying at its inner end a spur center 26. Herein the spindle 25 is shown as being mounted in the tailstock bearing through the medium of a sleeve 29 which is arranged to be reciprocated to move the spur center 26 toward and away from the center 16 by the operation of a lever 30 having a rack and pinion connection 28 with the sleeve.

In order that both centers 16 and 26 may be driven in synchronism I provide an operative connection between the spindles 15 and 25 comprising a shaft 31 having one end mounted in the headstock for rotational but non-longitudinal movement, and its other end slidably through a suitable bearing 32 in the tailstock. On the headstock spindle is a driving pinion 33 meshing with an intermediate or idler gear 34 which latter in turn meshes with a pinion 35 fast on the shaft 31. The intermediate gear 34

is supported by a bracket 36 on the headstock carrying a stud 37 upon which the intermediate gear is journalled. The stud 37 is adapted to be secured in the bracket 6 by means of a nut 38; and that part of the stud which is supported in the bracket 36 is of a diameter slightly less than the hole 39 in the bracket through which it passes. By this arrangement the intermediate gear 10 is capable of adjustment into proper mesh with the driving gear 33 and the pinion 35 so as to ensure that no lost motion or play shall occur in the transmission of power from the spindle 15 to the shaft 31. 15 A similar arrangement is provided in transmitting power from the shaft 31 to the tailstock spindle 25. Thus the tailstock spindle has fixed thereon a driven pinion 40 meshing with an intermediate gear 41, while 20 the latter meshes with a driving pinion 42 splined on the shaft 31 so as to be slideable with the tailstock relative to the shaft 31. The intermediate gear 41 is mounted on a bracket 43 which like the bracket 36 is 25 apertured at 45 to receive a stud 44 carrying the intermediate gear. The hole 45 in the bracket is somewhat larger than the diameter of the stud, as in the case of the headstock, so that here too any looseness or back-lash between the gears may be eliminated. 30 Inasmuch as the spindle 25 in the tailstock is mounted for longitudinal movement therein the intermediate gear 41 is made of substantial width so that the driven pinion 40 on the spindle may move axially relative to the gear 41 in the movements of the spindle while remaining in mesh with the gear 41.

It will be understood that the gears for 40 transmitting motion from the headstock

spindle to the shaft 31 and the gears for transmitting motion from the shaft 31 to the tailstock spindle 25 are similarly proportioned so that both spindles are driven at the same speed. The spur centers 16 and 26, therefore, positively engaging both ends 45 of the stick, drive the same in unison, thus avoiding any torsional stress in the stick and consequently eliminating effectually any chattering of the stick relative to the 50 cutter 9. Inasmuch as both ends of the stick are driven by spur centers, it is possible to turn the stick clear up to the ends, thereby obviating the necessity for any subsequent operation to cut off the unturned 55 portion and also avoiding waste of material.

It is essential to the successful driving of opposite ends of the stick that all looseness in the driving connections be eliminated, and the means which I have provided for mounting the intermediate gears is one method of effectually accomplishing this result.

I claim as my invention:

A wood turning machine comprising, in 60 combination, a base having a cutter mounted thereon, a table having a pair of work-supporting and driving spindles mounted in spaced relation, a spindle drive shaft on the table parallel to said spindles and gear 70 trains connecting opposite ends of the said shaft with the respective spindles to drive them in synchronism, said gear trains each comprising an intermediate gear adjustable relative to the adjacent gears of the train 75 to prevent back lash.

In testimony whereof, I have hereunto affixed my signature,

CARL LAWRENCE MATTISON.
